US00D858650S

(12) **United States Design Patent** (10) **Patent No.:** **US D858,650 S**
(45) **Date of Patent:** **** Sep. 3, 2019**

(54) **HANDHELD TOUCH OBJECT**

(71) Applicant: **Antsy Labs, LLC**, Dacono, CO (US)
(72) Inventors: **Matthew McLachlan**, Dacono, CO (US); **Mark McLachlan**, Frederick, CO (US)

(73) Assignee: **Antsy Labs, LLC**, Dacono, CO (US)

(**) Term: **15 Years**

(21) Appl. No.: **29/663,704**

(22) Filed: **Sep. 18, 2018**

Related U.S. Application Data

(63) Continuation of application No. 29/615,501, filed on Aug. 29, 2017, now Pat. No. Des. 829,828, which is a continuation-in-part of application No. 29/590,129, filed on Jan. 6, 2017, now Pat. No. Des. 818,054.

CLAIM

The ornamental design for a handheld touch object, as shown and described.

DESCRIPTION

FIG. 1 is a right, back and bottom perspective view of the handheld touch object showing our new design.

FIG. 2 is a top, front and left perspective view thereof.

FIG. 3 is a front elevation view thereof.

FIG. 4 is a back elevation view thereof.

FIG. 5 is a top plan view thereof.

FIG. 6 is a bottom plan view thereof.

FIG. 7 is a right side view thereof; and,

FIG. 8 is a left side view thereof.

The dashed lines represent features of the handheld touch object that form no part of the claimed design.

1 Claim, 5 Drawing Sheets
